BODY REST LOUNGE FOR SHAMPOOING

Beulah Molle, 2211 Santa Monica Blvd.,
Santa Monica, Calif. 90404

Filed Dec. 5, 1969, Ser. No. 20,376

Term of patent 14 years

Int. Cl. D6—01

U.S. Cl. D15—3

FIG. 1

FIG. 2

FIG. 3

FIG. 4

FIG. 5

FIG. 6

FIG. 1 is a perspective view of a body rest lounge for shampooing showing my new design;

FIG. 2 is a top plan view thereof;

FIG. 3 is a side elevational view thereof, showing the side opposite that which is shown in FIG. 1;

FIG. 4 is a front elevational view thereof;

FIG. 5 is a rear elevational view thereof; and,

FIG. 6 is a bottom plan view thereof.

I claim:

The ornamental design for a body rest lounge for shampooing, substantially as shown.
